UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

AUTOMATIC TELEPHONE SYSTEM.

1,340,934.

Specification of Letters Patent. Patented May 25, 1920.

Application filed December 4, 1917. Serial No. 205,336.

To all whom it may concern:

Be it known that I, HENRY P. CLAUSEN, a citizen of the United States, residing at Mount Vernon, in the county of Westchester, State of New York, have invented certain new and useful Improvements in Automatic Telephone Systems, of which the following is a full, clear, concise, and exact description.

10 This invention relates to telephone exchange systems and more particularly to telephone systems employing machine switching.

One object of this invention is to provide 15 an improved arrangement whereby a calling line may be seized as a called line while the calling subscriber has his receiver off the switchhook. Another object is the provision of improved means for immediately 20 releasing a connection in case the called line is busy.

In the operation of automatic telephone exchange systems a calling subscriber usually receives a busy tone in case the called 25 line is found busy. Frequently there is considerable delay before the calling subscriber thoroughly recognizes this busy signal and replaces his receiver upon the switchhook to render his line accessible as a called line.

30 A feature of this invention is the provision of means for producing the immediate release of a connection between a calling line and a called line if the called line is found busy. Another feature of this invention is the provision of means whereby a 35 calling line is made selectable as a called line before the calling party hangs up his receiver in response to a busy tone.

It is thought that the invention will be 40 best understood from the following description, reference being had to the accompanying drawings which diagrammatically represent in Figs. 1 and 2 the circuits of an automatic telephone system for connecting 45 two subscribers' lines together for conversation.

When the subscriber at station A removes his receiver from the hook, a circuit is completed from grounded battery, contact 1, winding of relay 2, right-hand armature and contact of relay 10, outer left-hand armature and back contact of plunger magnet 3, sender 4, loop of substation A, inner left-hand armature and back contact of 50 plunger magnet 3, left-hand winding of

busy tone apparatus 70 to ground. Relay 2 energizes and completes a circuit from grounded battery, left-hand high resistance winding of plunger magnet 3, armature and contact of relay 2 to ground. Plunger magnet 3 becomes energized and attracts plunger 5 to extend the calling line to an idle selector switch. As soon as the contacts 6 and 7 are closed a circuit is completed from grounded battery, upper winding of relay 60 71, contact 8, upper armature and back contact of relay 9, contact 6, right winding of polarized relay 10, sender 4, loop of substation A, contact 7, inner lower armature and back contact of relay 9, contact 11, lower winding of relay 71 to ground. The current flows over this circuit just described in the wrong direction to cause the polarized relay to attract its armature at this time. Relay 71, however, becomes energized and 75 completes a circuit from grounded battery, winding of slow release relay 12, armature and front contact of relay 71 to ground. Relay 12 completes a locking circuit for the plunger magnet 3 from grounded battery, 80 contact 1, right-hand low resistance winding of plunger magnet 3, contact 13, inner armature and front contact of relay 12 to ground. This ground at the inner armature and front contact of relay 12 is also connected to terminal 34' and multiples thereof 85 to cause the calling line to test busy when tested as a called line.

The calling subscriber now operates his dial 4 to cause a series of interruptions in 90 the line circuit. Upon the first deenergization of line relay 71, a circuit is completed from grounded battery, winding of magnet 17, winding of slow release relay 18, lower armature and front contact of relay 95 12, lower armature and back contact of relay 9, lower armature and back contact of relay 19, armature and back contact of relay 71 to ground. Magnet 17 is energized and advances the brush shaft (not shown) one 100 step in its primary movement. Relay 18 also is energized and closes a circuit from grounded battery, winding of relay 20, armature and front contact of relay 18 to ground. Relay 20 closes a locking circuit 105 for itself from grounded battery, winding of relay 20, upper armature and front contact of relay 20, contact springs 21, secondary off-normal contact 22, primary off-normal contact 23, inner armature and front 110

contact of relay 12 to ground. Magnet 17 is energized in response to each interruption of the line circuit, but relays 12 and 18 are so constructed that they hold their armatures attracted during the short interruptions produced in their energizing circuits during the sending of the impulses. Upon the completion of the first series of impulses, at which time the brush shaft (not shown) has been moved, so that the brushes 26, 27 and 28 are in operative relation with the desired group of trunks, line relay 71 remains energized for a sufficient length of time to cause the relay 18 to deenergize. A circuit is then completed from grounded battery, winding of secondary magnet 24, armature and back contact of secondary magnet 24, primary off-normal contact 25, armature and back contact of relay 18, upper armature and front contact of relay 20, contact springs 21, secondary off-normal contact 22, primary off-normal contact 23, inner armature and front contact of relay 12 to ground. The energization of magnet 24 moves the brushes 26, 27 and 28 into engagement with the first set of terminals of the selected group of trunks. If the trunk connected to this set of terminals is busy, ground will be found upon the test terminals 32 thereof, and the locking circuit of relay 20 will be completed through the brush 28, terminal 32 to this ground. It will be observed that the previously described locking circuit of relay 20 is open at contact 22 upon the first secondary step of the switch. Since the secondary magnet interrupts its own energizing circuit by attracting its armature, it will immediately deenergize and again complete a circuit for itself from grounded battery, winding of secondary magnet 24, armature and back contact of secondary magnet 24, primary off-normal contact 25, armature and back contact of relay 18, upper armature and front contact of relay 20, contact springs 21, brush 28, terminal 22 to ground, to move the brushes 26, 27 and 28 into engagement with the next set of terminals. This operation continues until an idle trunk is found, at which time no ground will be found upon the test terminal 32 thereof. Relay 20 then deenergizes and completes a circuit from grounded battery, winding of relay 9, upper armature and back contact of relay 20, contact springs 21, lower armature and back contact of relay 20, primary off-normal contact 23, inner armature and front contact of relay 12 to ground. Relay 9 by attracting its inner armatures opens the circuit of relay 71 and also extends the calling line through to the brushes 26 and 27. Relay 71 deenergizes and opens the circuit of relay 12.

A circuit is now closed from grounded battery, upper winding of relay 33, contact 34, terminal 30, brush 26, upper armature and

front contact of relay 9, contact 6, right-hand winding of relay 10, sender 4, loop of substation A, contact 7, inner lower armature and front contact of relay 9, brush 27, terminal 31, contact 35, lower winding of relay 33 to ground. The current flowing through this circuit is still in the wrong direction to cause the polarized relay 10 to attract its armature. Relay 33, however, becomes energized and closes a circuit from grounded battery, winding of slow release relay 36, armature and front contact of relay 33 to ground. Relay 36, by attracting its upper armature, connects ground to the terminal 32 to maintain the relay 9 and plunger magnet 3 energized, this circuit being closed before the slow release relay 12 has time to retract its armatures. This ground also prevents the connector switch from being seized by any other selector switch.

The subscriber at substation A now operates the sender 4 to produce a second series of interruptions in the line circuit. The first interruption causes the relay 33 to deenergize and close a circuit from grounded battery, side-switch arm 37 in its first position, winding of primary magnet 38, winding of slow release relay 39, lower armature and front contact of relay 36, 95 armature and back contact of relay 33 to ground. Magnet 38 is energized and advances the brush shaft (not shown) one step in its primary movement. Relay 39 is also energized and closes a circuit from grounded battery, winding of escapement magnet 40, armature and front contact of relay 39 to ground. Magnet 38 is energized in response to each interruption of the line circuit, but relays 36 and 39 are so constructed that they hold their armatures attracted during the transmission of the impulses. After the impulses have been sent, at which time the brush shaft (not shown) has been moved so that the brushes 48, 49 and 50 are 110 in operative relation with the group of terminals containing the called line, the relay 33 remains energized a sufficient length of time to cause the relay 39 to deenergize. Relay 39, by retracting its armature, opens the circuit of magnet 40, which deenergizes and moves the side-switch arms into their second position. The subscriber at substation A now operates the sender 4 to produce a third series of interruptions in the 120 line circuit. The first interruption causes the relay 33 to deenergize and complete a circuit from grounded battery, side-switch arm 37 in its second position, secondary magnet 41, upper armature and back contact 125 of relay 42, winding of relay 39, lower armature and front contact of relay 36, armature and back contact of relay 33 to ground. Magnet 41 is energized and moves the brushes 48, 49 and 50 into engagement 130

with the first set of terminals in the selected group. Likewise magnet 41 is energized in response to each succeeding interruption, but relays 36 and 39 remain energized during the transmission of the series. Upon the completion of this third series of impulses, the brushes are in engagement with the desired line. The relay 39 deenergizes in the same manner as above described. If the 5 called line is idle no ground is found upon the terminal 54, so that the magnet 40 then deenergizes and moves the side-switch arms into their third position. A circuit is now closed from grounded battery, winding of 10 relay 47, armature and back contact of relay 40, side-switch arm 64 to ground. A circuit is also completed from grounded battery, side-switch 37 in its third position, upper armature and back contact of relay 15 43, winding of relay 44, interrupter 45 to ground. Each time the interrupter closes this circuit, the relay 44 energizes and closes a circuit from ringing generator 46, left-hand armature and front contact of relay 44, 20 upper armature and front contact of relay 47, brush 48, terminal 52, sender 51, ringer at substation B (not shown), terminal 53, brush 49, lower armature and front contact of relay 47, right-hand armature and front 25 30 contact of relay 44, to the ringing generator 46. Ringing current is thus intermittently applied to the called line.

As soon as the subscriber at substation B removes his receiver from the hook and 35 the relay 44 is deenergized, a circuit is completed from grounded battery, upper winding of relay 55, left-hand armature and back contact of relay 44, upper armature and front contact of relay 47, brush 48, terminal 52, sender 51, loop at substation B, 40 terminal 53, brush 49, lower armature and front contact of relay 47, right-hand armature and back contact of relay 44, lower winding of relay 55, to ground. Relay 55 45 becomes energized and completes a circuit from grounded battery, side-switch arm 37 in its third position, winding of relay 43, armature and front contact of relay 55, primary off-normal contact 56 to ground. 50 Relay 43 becomes energized and by attracting its upper armature opens the circuit of the relay 44. Relay 43 by attracting its inner lower armature closes a locking circuit for itself from grounded battery, side- 55 switch arm 37 in its third position, winding of relay 43, inner lower armature of relay 43, primary off-normal contact 56 to ground. The subscribers' lines are now connected together for conversation.

60 When disconnection is desired the subscriber at substation A replaces his receiver upon its hook, relay 33 deenergizes and opens the circuit of relay 36. Relay 36 deenergizes and completes a circuit from 65 grounded battery, winding of release magnet 57, primary off-normal contact 58, lower armature and back contact of relay 36, armature and back contact of relay 33 to ground. Under the control of the release magnet 57, the connector switch is returned to its normal position. As soon as the relay 36 deenergizes it opens a circuit of relay 9 and plunger magnet 3. Relay 9 deenergizes and completes a circuit from 70 grounded battery, winding of release magnet 59, primary off-normal contact 60, lower armature and back contact of relay 12, lower armature and back contact of relay 9, lower armature and back contact of relay 19, armature and back contact of relay 71 to ground. Under the control of release magnet 59, the first selector switch is returned to its normal position. The plunger magnet 3 deenergizes and returns 75 the line switch to its normal position. 80 85

If the called line is busy, ground is found upon the test terminal 54 thereof, and therefore, when the relay 39 deenergizes, after the third set of impulses, the magnet 40 is still held energized due to a circuit being 90 closed from grounded battery, winding of magnet 40, contact 62, winding of relay 42, contact 63, side-switch arm 64, in its second position, brush 50, terminal 54 to ground. Relay 42 becomes energized and closes a 95 locking circuit for itself from grounded battery, winding of magnet 40, contact 62, winding of relay 42, inner lower armature and front contact of relay 42, primary off-normal contact 56 to ground. Relay 42 also 100 closes a circuit from grounded battery, winding of relay 65, lower armature and front contact of relay 42 to ground. Relay 65 by attracting its armatures reverses the connection of the battery to the calling line. 105 Current now flows in the proper direction through the right-hand winding of the polarized relay 10 to cause this relay to energize. Relay 10 closes a locking circuit for itself from grounded battery, armature and front contact of relay 10, left-hand winding of relay 10, right-hand armature and front contact of relay 3 to ground. The energization of relay 10 opens the circuit through the right-hand winding of the 110 plunger magnet 3 so that the plunger 5 is released. Since the relay 10 is made slow to retract its armatures, it is still held energized, due to a circuit completed from 115 grounded battery, armature and front contact of relay 10, left-hand winding of relay 10, right-hand armature and back contact of plunger magnet 3, sender 4, loop of substation A, inner left-hand armature and back contact of plunger magnet 3, left-hand 120 winding of busy tone apparatus 70 to ground. The busy tone is thereby connected to the calling line. The energization of relay 10 maintains the circuit of relay 2 open and thereby prevents the operation of 125 130

the line switch associated with the calling line.

As soon as the calling subscriber, after hearing the busy signal, replaces his receiver on the switchhook, the circuit through the left-hand winding of relay 10 is opened, thereby causing this relay to deenergize. The line switch is now in condition to extend the subscriber's line to an idle selector switch when the subscriber again removes his receiver from the switchhook to initiate a call.

At the time the plunger 5 was released by the energization of relay 10, the circuit of relay 33 was opened at contacts 6 and 7. This relay 33 deenergized and caused the release of the connector and the first selector switches in the same manner as above described.

Let us assume that while the busy signal is connected to the line leading to station A and before the subscriber thereat has replaced his receiver upon the switchhook, that a connector switch, whose brushes are designated 48', 49' and 50', seizes the terminals 52', 53' and 54' of this particular line. Since the contact 13 is open at this time, no ground will be found upon the test terminal 54. The side switch of the connector switch thereupon moves into its third position. Since the subscriber at substation A has his receiver off the hook, a circuit is closed from grounded battery, upon winding of a relay corresponding to relay 55, left-hand armature and back contact of a relay corresponding to relay 44, upper armature and front contact of a relay corresponding to relay 47, brush 48', terminal 52', right-hand winding of relay 10, sender 4, loop at substation A, terminal 53', brush 49', lower armature and front contact of the relay corresponding to relay 47, right-hand armature and back contact of the relay corresponding to relay 44, lower winding of relay 55 to ground. The current flowing through this circuit is in the direction to neutralize the effect of the current through the left-hand winding of relay 10. Therefore relay 10 deenergizes and completes a circuit from grounded battery, contact 1, right-hand low resistance winding of plunger magnet 3, test terminal 54', brush 50', through a side-switch arm corresponding to side-switch arm 64 to ground. The current flowing through this low resistance winding of the plunger magnet 3 is sufficient to cause the magnet to attract its left-hand armatures, but is not sufficient to cause the magnet to attract the plunger 5. Plunger magnet 3 is so arranged that it attracts its left-hand armature more quickly than the relay 2 attracts its armature, otherwise the relay 2 would become energized and close a circuit through the left-hand high resistance winding of plunger magnet 3 to attract the plunger 5.

It is thus observed that the subscriber at station A may now converse, as a called party, with the calling party. Since the release of the switches used in establishing this last telephonic connection is accomplished in the same manner as above described, further description is deemed unnecessary.

What is claimed is:

1. In a telephone system, a calling line, 75 a called line, a non-numerical switch associated with said calling line, numerical switches, means for operating said switches to establish a connection between said calling and called lines, a busy signaling device, 80 a polarized relay associated with said non-numerical switch and means for reversing the current through the polarized relay for operating said relay to connect said busy signaling device to said calling line if said called line is busy.

2. In a telephone system, a calling line, a called line, a non-numerical switch associated with said calling line, numerical switches, means for operating said switches to establish 90 a connection between said calling and called lines, a busy signaling device, a single relay associated with said non-numerical switch arranged to control the release of said numerical switches and the connection of said 95 busy signaling devices to said calling line, and means associated with said numerical switches for operating said relay to release said numerical switches and to connect said busy signaling device to said calling line if 100 said called line is busy.

3. In a telephone system, a calling line, a called line, a non-numerical switch associated with said calling line, numerical switches, means for operating all of said 105 switches to establish a connection between said calling and said called lines, a relay associated with said non-numerical switch arranged to control the release of all said switches, means for operating said relay to 110 release said switches if said called line is busy, and means for maintaining said relay energized to render said non-numerical switch inoperative until the calling party hangs up his receiver.

4. In a telephone system, a calling line, a called line, a non-numerical switch associated with said calling line, numerical switches, means for operating all of said switches to establish a connection between 120 said calling and said called lines, a relay associated with said non-numerical switch arranged to control the release of all said switches, means for closing an operating circuit for said relay to release said switches if 125 said called line is busy, and a locking circuit for said relay completed over said calling line to render said non-numerical switch inoperative until after the calling party hangs up his receiver.

5. In a telephone system, a calling line, a called line, means including a non-numerical switch individual to said calling line for establishing a connection between said calling and called lines, means for rendering said calling line non-selectable as a called line during the establishment of said connection, a busy signaling device, means for releasing said connection and for connecting said busy signaling device to said calling line if said called line is busy, and means controlled by said last mentioned means for rendering said calling line selectable as a called line before the calling party hangs up his receiver in response to said busy tone.
6. In a telephone system, a calling line, a called line, means including a non-numerical switch associated with said calling line for establishing a connection between said calling and called lines, means for rendering said calling line non-selectable as a called line during the establishment of said connection, a relay associated with said non-numerical switch, a busy signaling device, means for closing an operating circuit for said relay if said called line is busy, means controlled by the operation of said relay for releasing said connection and for connecting said busy signaling device to said calling line, means controlled by the release of said non-numerical switch for rendering said calling line selectable as a called line before said calling party hangs up his receiver in response to said busy signaling device, and means operated if said calling line is selected as a called line before the calling party hangs up his receiver for disconnecting said busy signaling device from said calling line and for maintaining said non-numerical switch inoperative.
7. In a telephone system, a calling line, a called line, a non-numerical switch associated with said calling line, means for rendering said calling line non-selectable as a called line during the establishment of a connection, and means for rendering said
- non-numerical switch inoperative if said called line is busy and thereby rendering said calling line selectable as a called line before the calling party hangs up his receiver.
8. In a telephone system, a calling line, a called line, means including a non-numerical switch individual to said calling line for establishing a connection between said calling and called lines, means for rendering said calling line non-selectable as a called line during the establishment of said connection, and means for rendering said calling line selectable as a called line before the calling party hangs up his receiver if said called line is busy.
9. In a telephone system, a calling line, a called line, a non-numerical switch associated with said calling line, numerical switches, means for operating all of said switches to establish a connection between said calling and said called line, a relay associated with said non-numerical switch arranged to control the release of all of said switches, and means for operating said relay to release said switches if said called line is busy and for maintaining said relay energized to render said non-numerical switch inoperative until the calling party hangs up his receiver.
10. In a telephone system, a calling line, a called line, a non-numerical switch associated with said calling line, numerical switches, means for operating all of said switches to establish a connection between said calling and said called lines, means arranged to control the release of all of said switches, and means for operating said releasing means to release said switches if said called line is busy and for rendering said calling line selectable as a called line until said calling party hangs up his receiver.

In witness whereof, I hereunto subscribe my name this 27th day of November A. D., 1917.

HENRY P. CLAUSEN.
